United States Patent Office

Des. 192,662
Patented Apr. 24, 1962

192,662

COMPUTING MACHINE OR THE LIKE

Peter Sieber, Frankfurt am Main Seckbach, Germany,
assignor to Olympia Werke A.G., Wilhelmshaven, Germany

Filed Apr. 3, 1961, Ser. No. 64,590

Term of patent 14 years

(Cl. D64—11)

Fig. 1.

Fig. 3.

Fig. 2.

Fig. 4.

FIG. 1 is a side perspective view of a computing machine showing my new design;

FIG. 2 is a perspective view thereof as seen from the other side;

FIG. 3 is a front view of the computing machine; and

FIG. 4 is a rear view thereof.

The essential features of the design reside in the portions shown in full lines on the drawing.

I claim:

The ornamental design for a computing machine or the like, as shown and described.
